UNITED STATES PATENT OFFICE.

HAROLD C. BEEBE, OF NEW HAVEN, CONNECTICUT.

COIN-CONTROLLED LOCK.

Application filed January 14, 1922. Serial No. 529,223.

This invention relates to locks and, more particularly, to coin controlled locks such as are adapted to be used upon the doors of pay toilets, or the like, so that the collection of the coin is automatically accomplished before entrance to the room may be effected by anyone desiring to use the toilet. It will be obvious, of course, that the lock is applicable to any door upon which it is desired to use a lock of this character, and some features of my improvements are not limited to coin controlled locks, but may be used in connection with ordinary locks or latches which do not include the coin operable mechanism.

One object of my invention is to simplify a device of this character while securing advantages of operation not found in the present structures.

Another object of my invention is to provide improved means for closing the coin slot when the door is open and keeping it closed after the door has been again closed and until it is opened from the inside by the occupant of the room. I contemplate the provision of means for accomplishing this function which shall be, to some degree, independent of the latch or lock bolt, so that once this mechanism has been set to close the slot, the bolt may still be operated from the outside of the door independently thereof and without releasing it so that the slot closing mechanism will not, thereby, be restored to its normal position.

Further objects of my invention are the provision of improved means for holding the coin in operative position to withdraw the latch bolt from the outside of the door until such time as the occupant enters the room and the latch bolt is retracted by contact with the strike plate; the provision of a meter or counter to register the number of times the room is used, which register will preferably be operated by part of the slot closing mechanism rather than by the operation of the bolt; and improved means for securing the operating parts of the structure within the case, securing the case itself upon the door, providing for the withdrawal of the coin therefrom and the provision of a door knob of improved construction.

To these and other ends, the invention consists of the novel features and combina-

tions of parts to be hereinafter described and claimed.

In the accompanying drawings:

Fig. 1 is a front elevational view of my improved lock mounted in operative position upon the door;

Fig. 2 is a side elevation of the parts shown in Fig. 1, showing an edge view of the door;

Fig. 3 is an inside elevational view of the cover of the lock case;

Fig. 4 is a front elevational view of the base plate adapted to be secured upon the door and upon which the operating mechanism is mounted;

Fig. 5 is a view similar to Fig. 4, but showing the parts in the position occupied by them when the knob has been turned after the insertion of the proper coin;

Fig. 6 is a view of the parts from the side opposite that shown in Fig. 4;

Fig. 7 is a sectional view on line 7—7 of Fig. 4;

Fig. 8 is a sectional view on line 8—8 of Fig. 4; and

Fig. 9 is a sectional view on line 9—9 of Fig. 5.

In the preferred embodiment of my invention illustrated in the drawings, I have shown a door 10 having a lock case 11 mounted thereon. Protruding from the lock case is the head 12 of a lock or latch bolt which cooperates with a strike plate 13 of approved form mounted upon the door frame or jamb 14. The lock case consists of a base plate 15 adapted to be secured upon the face of the door and upon which the greater part of the operating mechanism is mounted and a cover 16 adapted to be applied to the base plate after the latter is mounted in its proper position. This cover plate is provided with a strap 17 secured to the interior thereof which, in turn, may be secured to the base plate to hold the cover in position, and with two recesses 16^a to receive the pins 15^a on the upper edge of the base plate. At the upper part of the cover, is provided a coin slot 18 and rotatably mounted upon the front face of the cover is the outside door knob 19. Secured to the stem 20 of the knob is a roll-back 21 which, as will be more fully described hereinafter, operates to retract the bolt. Below the knob the cover plate is pro-

vided with an opening 22 within which is fitted a square plate 23 having a pair of lugs 24 at the upper side thereof adapted to overlap one margin of the opening and provided adjacent its lower edge with a key operated lock 25 which operates a locking member 26 adapted to engage a lug 27 adjacent the lower side of the opening 22 to lock the plate in position. Through this opening, when the plate 23 is removed by an authorized person having the proper key to fit the lock 25, the coins may be removed which have been collected by the lock mechanism.

15. The main part of the operating mechanism of the lock is, as has been stated heretofore, mounted upon the base plate secured upon the outer surface of the door. A bolt guide consisting of a pair of straps 29 and 30 is secured to the plate 15. These straps are connected by a front plate or web 31 and the strap 29 is closed at the rear side thereof by the end piece 32. Within the guideway thus formed is slidably mounted the bolt 33 having the beveled head 12 heretofore referred to. Within a recess in the rear end of this bolt is mounted a spring 34 and plunger 35, the latter acting against the end piece 32 to normally urge the bolt to protracted position. Slidably mounted upon the plate or web member 31 is an upstanding operating member 36 having a laterally disposed upper end 37 adapted to close the opening in the coin chute 38 when this slide is retracted by the knob. The body of the operating lever is disposed upon the outside of the plate 31, as best shown in Figs. 4 and 7. In order that this member may be properly guided in its movement, a strap 40 is mounted upon the member 36 and offset to extend upon the opposite side of the plate member 31 so that the operating slide will have an even sliding movement upon this plate. Upon the ends of this strap 40 are formed two talons 41 and 42 adapted to be engaged by the arms 43 and 44 of the rollback 21. The strap 40 is provided upon its rear edge with an arcuate recess 45 adapted to engage the edge of the coin as shown in Fig. 5. 50. The front face of the bolt is adapted to bear against the guides 29 and 30 at the portions thereof adjacent these two members, but between them the bolt is slightly recessed or cut away from its front face to provide a pair of shoulders, one of which is shown at 46 in Fig. 5. This shoulder is provided with a recessed portion 47 adapted to effect a positive release, at the proper time, of a coin delivered by the chute 38. It will be obvious that when a coin is deposited in the opening 18, passes down through the chute 38 and lodges between the shoulder 46 and recess 45, if the outside knob is turned to move the slide 36 from the dotted line position shown in Fig. 5 to the full line position shown

in that figure, this slide will act through the agency of the intervening coin to retract the bolt by means of the engagement of the coin with the member 40 attached to the slide and the shoulder 46 formed upon the bolt. 70

Upon the upper surface of the bolt is slidably mounted an operating slide 50. This slide is also received and guided within the strap members 29 and 30 while it is supported upon the upper edge of the bolt as shown in Fig. 7. The slide is provided with a slot or cutout portion 51, thus providing an opening through which the coin is adapted to pass as it leaves the chute 38. This opening terminates in the shoulders 52 and 53 as shown more especially in Figs. 8 and 9, and it will be apparent that when the parts are moved from the position shown in Fig. 4 to that shown in Fig. 5, the edge of the coin will engage the shoulder 52 and will also move the slide rearwardly at the same time that the bolt is retracted. Adjacent the forward portion of the slide at the rear edge thereof is provided a recess or cutout 54 adapted to receive one end of a lever 55 pivoted at 56 upon the plate 15. The upper end of this lever passes between a pair of laterally extending ears 57 and 58 formed upon a slot controlling slide 59, having at its upper edge a laterally extending lip 60 which is adapted in the position shown in Fig. 5 to lie just below the coin slot 18 and above the mouth of the chute 38 to prevent, when in this position, the insertion of a coin therein. The slide 59 may be operatively mounted upon the plate 15 in any approved way. In the form shown the slide is provided with a slot 61 which receives the shanks of a pair of screws 62 and 63, which as will be obvious will permit the member 59 to enjoy a free sliding movement. 100

Pivots mounted at 64 upon the supporting plate 15 is a second lever 65, one end of which is connected by a spring 66 to the upper arm of the lever 55. The lower end 110 of this lever 65 is provided with a hook 67, the end of which is adapted to rest upon the upper surface of the operating slide 50 as this slide is being moved from the position shown in Fig. 4 to that shown in Fig. 5. 115 The slide is also provided at its rear edge with an elongated recess or slot 68 which terminates at its rear end in the shoulder 69. When this slide is drawn rearwardly by the member 36 and the coin to the position shown in Fig. 5, the lever 65 is rocked in a clockwise direction by the spring 66 so that the point of the hook 67 engages the shoulder 69 and retains this slide in this rearward or retracted position. In this position the spring 66 has been tensioned by the swinging of the lever 55 in a clockwise direction about its pivot by means of the engagement of the lower end of this lever in the slot 54 in the operating slide. As shown 120

in Figs. 4 and 6, this spring is relieved of practically all of its tension, but when the parts are moved to the position shown in Fig. 5, it will be apparent that while the lever 55 is moved positively in a clockwise direction, pivotal movement of the lever 65 in the same direction is prevented by contact of the hook 67 with the upper surface of the slide 50. The spring 66 is therefore brought under tension and when the edge of the hook 67 lies opposite the opening 68, the hook will drop downwardly into engagement with the shoulder 69 to retain the slide in this retracted position.

15 A register or counter 70 is shown secured to the supporting plate 15 and is provided with an operating arm or crank 71. A link 72 connects this crank to an arm 73 upon the lever 55 so that when this lever is moved from the position shown in Fig. 4 to the position shown in Fig. 5, as it will be by the action of the outside knob and the operating slide 50, the counter will be operated through the link 72 to register the number 20 of times that the slide 50 is drawn back by means of the coin.

If when the parts are in the position shown in Fig. 5, the outside knob is released, as it will be in the ordinary use of the mechanism, the operating slide 50 will be retained in its rearward or retracted position while the spring 34 will again carry the latch bolt to its protracted position. The member 36 and the outside knob 19 will also be returned to their original positions by means of the spring 74 which is attached to the guide strap 30 at one end and to the member 36 at the other. When this occurs, the coin will drop down to a lower position so that it will no longer be engageable with the plate 50, but will still be retained between the edge of the member 40 and the shoulder 46. To force the coin to this lower position so that it will no longer engage the slide, a strap 75 is mounted upon this slide and is provided with a slightly offset shoulder 76 which projects over the slot 51 and, engaging the edge of the coin in the position shown in Fig. 5, forces the coin downwardly as the latter is moved to the right by the shoulder 46. It will be obvious that with the coin still held in position between the operating member and the shoulder, if by any chance a person after turning the knob releases it before opening the door, he will not be locked out as the latch bolt can again be retracted time after time by the coin to open the door, without, however, having any effect upon the slide 50 or the mechanism controlled thereby, including the counter or register 70. When, however, the person enters the room and closes the door, the latch bolt will be retracted by the engagement of the bevelled head thereof with the

strike plate and as at this time the operating member 36 remains stationary, the coin will be allowed to drop into a proper receptacle or the lower part of the case 11 for collection.

The door is now in closed position with the slot closed against the insertion of a coin and in ordinary use it will next be desired to open the door from the inside. For this purpose an inside knob 77 is mounted upon the door by means of the plate 78 secured to the door by screws 79 passing therethrough from the outside thereof, which screws are put into position before the application of the supporting plate 15. The plate 78 is provided with a central opening 80, into which fits a reduced portion 81 of the shank of the door knob, and to the face of this shank is secured a plate 82, thereby clamping the edge of the opening 80 in the plate 78 between a shoulder 83 on the knob shank and the plate 82 upon the face of the shank. The plate 82 is provided with a square opening into which is fitted a square shaft or bolt 85, one end of which passes into the hollow shank of the knob, the other end passing into a sleeve 84 rotatably mounted in the supporting plate 15 and provided with a square opening to non-rotatably receive the bolt 85. In this way the lock may be applied to doors of different thickness as the bolt 85 is slidably received in the plate 82 and considerable adjustment may be made before the end of the bolt would be withdrawn from this opening. To the sleeve 84 is secured a rollback 86 having arms 87 and 88 engaging talons 89 and 90 on a plate 90 secured to the bolt 85 adjacent the mounting plate 15 as clearly shown in Fig. 7. As best shown in Fig. 6, the rear face of the bolt 85 closely abuts the mounting plate 15 adjacent the bolt end, but intermediate its length the bolt is provided with a cutout or sliding portion 91 providing the shoulders 92 and 93. Within this slotted portion between the rear face of the bolt and the front face of the supporting plate 15 lie the plate 90 and the rollback 86 just described, and the lower end of the lever 55 which passes through a slot 54 in the operating plate 50. Also mounted within this space is a lever 94 pivoted to the supporting plate at 95 and having an upwardly projecting finger 96 in position to engage the lower arm of the lever 65. An edge face 97 of the other end of this lever lies against a straight portion 98 of the rollback 86 so that this lever will be operated when the rollback 86 is rotated by the inside knob. The end 96 of this lever then engages the lower hooked end of the lever 65 and rocking it in an anti-clockwise direction, as shown in Fig. 5, releases the operating slide 50 which, together with the associated mechanism, is moved back to its normal position shown in Fig. 4. This happens, of course, when the occupant opens the

door to emerge from the room, so that the parts are thereby set for a subsequent operation when a proper coin is dropped in the slot. At this time the slide 59 moves to the position shown in Fig. 4 to uncover the mouth of the coin chute 38 and the counter arm 71 is dropped from the position shown in Fig. 5 to the position shown in Fig. 4 preparatory to another operation.

If a coin smaller than the proper one is dropped in the coin slot 18, it will pass down through the chute and entirely through the mechanism without lodging in the position in which the proper coin is shown in Figs. 4 and 5, that is, the shoulder of the recess 45 and the shoulder 46 will be separated too far to retain this coin in position to operate the bolt. In some cases, however, the bolt might be operated by turning the outside knob slightly so that the recess 45 would be moved closer to the shoulder 46 prior to the insertion of the coin in the slot. The office of the laterally extending lip 37 is to prevent any fraud in this respect as, when the knob is turned to operate the member 36, the lip 37 will be carried over the mouth of the coin chute 38 so that any coin which will be permitted to pass into the chute will fall idly through the lock mechanism and will not be retained between the shoulders 45 and 46 in position to operate the bolt.

The operation of my improved mechanism is as follows: The door being closed and the parts in the position shown in Fig. 4, it will be apparent that it is impossible to retract the latch by rotation of the outside knob 19, as the operating member 36 has no connection with the latch bolt except through the intervention of the proper coin. When, however, the proper coin is inserted into the slot 17 and drops through the chute 38 to the position shown in Fig. 4, it establishes a connection between the edge of the recess 45 in the operating member 36 and the shoulder 46 of the bolt. The bolt may now be retracted by the rotation of the knob. The coin also at this time, by contact with the shoulder 52 of the slide 50, draws this slide rearwardly, together with the lower end of the lever 55 until the lower hooked end 67 of the lever 65 engages the shoulder 69 in this slide. The parts are now in the position shown in Fig. 5, the upper end of the lever 55 having moved the slot closing slide 59 to the right into operative position to close the slot and having drawn the counter arm upwardly to actuate the counter mechanism and indicate the reception of the coin. The door may now be opened and the knob released, the spring 74 drawing the knob and operating member 36 to the right to their normal positions and the bolt being again protracted by the spring 34. Should, however, the operator release the knob before the door was opened so that

the latch bolt is still retained by the door strike 13, the bolt may still be retracted by the knob as the coin has not yet dropped into the receptacle provided for it, as will now be explained. When the knob is released and the latch bolt is again protracted by the spring 34, the coin is moved to the right, as shown in Fig. 5, by the pressure of the edge of the shoulder 46. The right hand edge of the coin contacts with the part 76 of the plate 75, and while the coin is forced down to a position below this plate, it is still retained between the shoulder 46 and the member 40 upon the operating member 36, as shown at 103 in Fig. 4. The part 76 at this time closes the lower end of the coin chute. The slide 50 is, of course, held in the position shown in Fig. 5 by means of the engagement of the hook 67 therewith, as are also the slide 59, the lever 55 and the counter arm 71, all of which are controlled by the slide. When a person passes into the room and closes the door, the latch bolt is retracted by operation of the strike and the shoulder 46 moves away from the edge of the member 40, thus allowing the coin to drop out of operative position into a proper receptacle, the remaining parts, however, still being retained in the position shown in Fig. 5. In this position, the lower arm of the lever 55 contacts with the upper end 96 of the lever 94 so that when the occupant of the room wishes to emerge and rotates the inner knob 77 to withdraw the latch bolt, the rollback 86 rotates the lever 94 and thus moves the hooked end of the lever 65 out of engagement with the shoulder 69 on the slide 50, the spring 66 restoring the slide and associated mechanism to their normal positions. The lock is now set for a succeeding operation.

It will also be obvious that I have provided both inside and outside knobs with operating mechanism which enables them to be rotated in either direction to retract the latch bolt, which is not usual in a coin controlled lock.

It is necessary at times for an attendant to be able to open the door from the outside without the necessity of inserting the coin into the slot. This may be done by means of a proper key inserted through the keyhole 100 in the cover plate 11, the key bit 101 engaging a depending pin 102 upon the lower edge of the bolt 33.

While I have shown and described a preferred embodiment of my invention, it is to be understood that the same is not limited to the exact details shown, but is capable of modifications and variations which fall within the spirit of the invention and within the scope of the appended claims.

What I claim is:

1. In a coin controlled lock, a bolt, means

- providing a coin slot, a manually operated member, slot closing means, an operating slide for said means, means for positioning a coin between the manually operated member and the bolt and slide, whereby when the coin is moved by the manually operated member it will act against and move the bolt and slide, means upon said slide to move the coin out of engagement with the slide upon the return of the bolt to protracted position, means for maintaining the slide in slot closing position, and a spring to return it to normal position upon its release.
2. In a coin controlled lock, a bolt, a manually operated member, means for positioning a coin between said bolt and member to effect a movement of the bolt by the manually operated member, a slide positioned to be acted upon by said coin, means upon said slide to move the coin out of engagement therewith upon a return movement of the bolt to protracted position, and means connected to the slide to prevent the insertion of a coin into the mechanism, means to retain said slide in position to prevent such insertion, means operable from the inside of the door to release said retaining means, and a spring to return said slide to its normal position.
3. In a lock, a reciprocating bolt, means to retract the bolt through the agency of a coin, a slide retracted with the bolt, a lever connected with the slide and with a slot closing member, a detent to engage said slide, and a spring connected to said detent and to said lever.
4. In a lock, a reciprocating bolt, means to retract the bolt through the agency of a coin, a slide retracted with the bolt, a lever connected with the slide and with a slot closing member, a detent to engage said slide, and a single spring to urge said detent to engaging position, and said slot closing means to inoperative position.
5. In a coin controlled lock, a reciprocating bolt, knob operated means to retract said bolt through the agency of a coin, a slide arranged adjacent the bolt and adapted to be operated by the coin when the bolt is retracted, a coin slot, a slide adapted to cover said slot, and a lever pivoted to the lock case and having its ends respectively connected with said slides whereby the slot will be covered when the bolt is retracted, means for locking the coin operated slide in retracted position, and a spring to restore said slide to normal position.
6. In a coin controlled lock, a reciprocating bolt, knob operated means to retract said bolt through the agency of a coin, a slide arranged adjacent the bolt and adapted to be operated by the coin when the bolt is retracted, a coin slot, a slide adapted to cover said slot, a lever pivoted to the lock case and having its ends respectively connected with
- said slides whereby the slot will be covered when the bolt is retracted, and means for locking said coin operated slide in retractive position.
7. In a coin controlled lock, a reciprocating bolt, knob operated means to retract said bolt through the agency of a coin, a slide arranged adjacent the bolt and adapted to be operated by the coin when the bolt is retracted, a coin slot, a slide adapted to cover said slot, a lever pivoted to the lock case and having its ends respectively connected with said slides whereby the slot will be covered when the bolt is retracted, a detent engaging said coin operating slide to lock it in retractive position, and a spring connected to said detent and said lever to urge the slide to its protractive position and to urge the lever to operative position.
8. In a coin controlled lock, a lock case provided with a coin slot and a reciprocable bolt, knob operated means upon one side of the lock to operate the bolt through the agency of a coin, a slide mounted adjacent the bolt and adapted to be moved by the coin when the bolt is retracted, a slot closing element connected to the slide for operation thereby, means to hold said slide in retracted position and means to cause said coin to move out of engagement with said slide without being disengaged from the bolt when the knob is released.
9. In a coin controlled lock, a reciprocating bolt, knob operated means to retract said bolt through the agency of a coin, a slide arranged adjacent the bolt and adapted to be operated by the coin when the bolt is retracted, a coin slot, a slide adapted to cover said slot, a lever pivoted to the lock case and having its ends respectively connected with said slides whereby the slot will be covered when the bolt is retracted, a detent engaging said coin operating slide to lock it in retractive position, a spring connected to said detent and said lever, to urge the slide to its protractive position and to urge the lever to operative position, and means operated by the turning of the knob on the opposite side of the door for releasing said detent.
10. In a door lock, a bolt, manually operable means upon the outside of the door to retract the bolt through the agency of a coin, a slide retracted with the bolt, means to retain said slide in retracted position, means upon the slide to force the coin downwardly out of contact therewith upon the return of the bolt to protracted position to permit a subsequent retraction of the bolt by the same coin without the operation of the slide, and registering means connected with the slide to be operated thereby.
11. In a door lock, a bolt, manually operable means upon the outside of the door to retract the bolt through the agency of a coin,

6
coin, a slide retracted with the bolt, means to retain said slide in retracted position, means upon the slide to force the coin downwardly out of contact therewith upon the return of the bolt to protracted position to permit a subsequent retraction of the bolt by the same coin without the operation of the slide, registering means connected to the slide to be operated thereby, and slot closing means operated by the slide whereby said slot closing means and registering means will not be operated by subsequent retractions of the bolt by the same coin.

12. In a coin controlled lock, a case provided with a coin slot, a reciprocating bolt mounted in the case, means on the outside of the door to retract said bolt through the

agency of a coin, a slide arranged adjacent the bolt and adapted to be retracted therewith, a slot closing element connected to the slide to be operated thereby, means to retain the slide in retracted position, manually operable means upon the inside of the door to release said retaining means, and a spring to return the slide and slot closing element to their normal positions upon the release of said retaining means, and means upon said slide to force the coin downwardly out of contact therewith upon a return movement of the bolt while the coin is retained in engagement with the bolt.

In witness whereof, I have hereunto set my hand on the 12th day of January, 1922.

HAROLD C. BEEBE.
